SLIDER

Gideon Sundback, Meadville, Pa., assignor to
Hookless Fastener Company, Meadville, Pa., a
corporation of Pennsylvania

Application July 22, 1933, Serial No. 681,721

2 Claims. (Cl. 24—205)

My invention relates to separable interlocking fasteners and particularly to sliders for such fasteners.

The invention is intended primarily for non-metallic fasteners although it can be used to advantage with certain metallic fasteners.

An object of the invention is to provide a wear resisting surface on the parts of a slider which are most subject to wear. In sliders made from metal, there is not much difficulty encountered on account of the wear of the slider, except in long lengths of fastener chain such as applied to tents, rugs, etc. However, recent experiments with slide fasteners made from cellulosic nitrate material have demonstrated that objectionable wear is likely to occur on the slider in ordinary use.

According to my invention there are attached on the inner surfaces of the slider flanges which are most subject to wear, small pieces of wear resisting material. In one desirable embodiment, metal plates are anchored in place on the slider flanges but it is believed that certain non-metallic materials will be found useful for the purpose. A pressed fiber material attached to the slider flanges would wear better than the cellulosic nitrate material of the slider body. It may in some cases be desirable to make the body portion of the slider of relatively soft plastic material such as cellulose nitrate and the flanges or portions of them of relatively hard plastic material, such as bakelite. It is also believed that certain impregnated fabric materials would be useful for the purpose. Any thin fabric section can be stuck in place on the flanges by the use of solvent to soften the cellulose nitrate material sufficiently to cause it to adhere to the fabric.

In the accompanying drawing I have shown for purposes of illustration several embodiments of my invention. In the drawing:

Fig. 1 is a general view of a slide fastener constructed in accordance with my invention.

Fig. 2 is a cross-section on line 2—2 of Fig. 1; Fig. 3 is a perspective view of one-half of a slider;

Fig. 4 illustrates a second embodiment; and

Figs. 5 and 6 illustrate still other embodiments, Fig. 6 showing a wear resisting insert of fibrous material.

The fastener shown in Fig. 1 is a common form having flexible supports, herein fabric tapes 7, with interlocking elements 8 attached thereto in uniformly spaced relation. The particular shape of the interlocking elements forms no

part of the present invention and the ones illustrated are provided with projections 9 which engage in recesses on the opposed interlocking members in a manner which is well-known in the art. For the purpose of interlocking and releasing the elements there is provided a slider 10 having a pull member 11 attached thereto for actuating the same.

The slider comprises a body of generally key- 10 stone-shape having a Y-shaped channel 12 there- in. The slider body has opposed parallel wings 13 connected at one end by a triangular shaped neck 14 and having side flanges 15. The flanges bear against the ends of the interlocking elements and it is at this point that most of the wear 15 occurs in the slider. This is due to pulling the fastener together under more or less lateral strain. The greatest wear occurs within the narrow end of the slider where the interlocking elements are brought into intermeshed relation. 20

The wear resisting plates 16 are attached to the inner surfaces of the slider flanges in such positions that they will be concealed from view and preferably, though not necessarily extend the full length thereof. In the case of non-me- 25 tallic wear resisting materials or even with me- tallic materials, provided the surfaces are roughened, the wear plates may be stuck in place by cement, glue or similar bonding material or if the slider body is of soluble material, the wear pieces 30 may be stuck in place by softening the material with solvent sufficiently to cause the wear pieces to adhere firmly to them. 35

In Fig. 4 the entire slider flange 17 is formed of the wear resisting material and can be at- 35 tached to the flat slider wings by any suitable means. In Fig. 5 there is shown a convenient way of attaching a wear plate, particularly when the plate is made of metal. The lugs 18 are turned outwardly at the ends of the wear pieces 40 to engage over the ends of the slider flanges. In Fig. 6 only the lower ends of the flanges are im- pregnated with wear resisting material. This is accomplished by inserting a member 19 across the end of the slider and having upturned ends 45 20 extending along the inner surfaces of the flanges. The member 19 can be fixed in place in the manner above described or by any suitable method. 50

While I have shown and described in this ap- plication one specific form and several other em- bodiments which my invention may assume in practice, it will be understood that these em- bodiments are merely for the purposes of illustration

and description and that various other forms may be devised within the scope of my invention as described in the appended claims.

What I claim as my invention is:

- 5 1. A slider for separable interlocking fasteners of the class described, comprising a body of generally keystone-shape having a Y-shaped channel therein, the body having opposed wings and a neck connection at one end of the wings, 10 said wings having side flanges extending toward each other which flanges bear against the ends of the fastener elements in closing the fastener, the slider body consisting of a relatively low wear resistant non-metallic material to match the material of non-metallic fastener elements, and substantially concealed metal plates anchored in 15 place on the slider flanges so as to provide rela-

tively high wear resistant inner surfaces on said flanges.

2. A slider for separable interlocking fasteners of the class described, comprising a body of generally keystone-shape having a Y-shaped channel therein, the body having opposed wings and a neck connection at one end of the wings, 5 said wings having side flanges extending toward each other which flanges bear against the ends of the fastener elements in closing the fastener, the slider body consisting of a relatively low wear resistant non-metallic material, and wear resistant pieces anchored in place on the slider flanges in such positions as to be concealed from view so as to provide relatively high wear resistant surfaces on said flanges. 10 15
